AERIAL TRACK

1,038,089.

Specification of Letters Patent. Patented Sept. 10, 1912.

Application filed July 25, 1910. Serial No. 578,646.

To all whom it may concern:

Be it known that I, BERNHARD CLAUSEN, engineer, a subject of the King of Prussia and German Emperor, residing at 23 Holzlandesche Strasse, in the city of Dortmund, in the Kingdom of Prussia, German Empire, have invented certain new and useful Improvements in Aerial Tracks, of which the following is a specification.

10. The invention relates to an aerial support for traveling cranes, and especially to a construction in which one or more cables comprise the track on which the crane travels.

15. An object of the invention is to provide a traveling crane for factories, etc., whereby a load may be transported between two relatively distant points on a system of cables, wires, etc., which are horizontally disposed 20 and are supported only at their opposite ends.

Difficulties have been experienced in providing long spans of cable tracks and electric conductors supported thereby. I solve 25 the problem by supporting cables at their ends only, and by connecting them at intervals between their ends by spacing beams, which hold the cable tracks for the current collector parallel to each other, and at the same time hold the electric conductors which 30 are thus supported at intervals, although the cables are supported only at their ends. The cables support the weight of the conductors at frequent points, thereby maintaining the 35 conductors parallel to each other and holding them steady. The supporting posts for the cables and conductors may be at great distances apart, and yet the conductors need have only the diameters required for their 40 electrical work.

I attain the foregoing objects by the mechanism illustrated in the accompanying drawings, in which similar reference characters designate similar parts throughout 45 the several views and in which—

Figure 1 is a side elevation, showing a fragment of the track with the current remover seated thereon. Fig. 2 is a plan view of Fig. 1. Fig. 3 is a diagrammatic end view of the structure seen in Fig. 2, the 50 cables being in section.

Electric conductors are represented by *k* and are supported on insulators *l*, secured to

transversely disposed spacer beams *m*, which are suspended from supporter cables *n*. These beams *m* are suitably spaced apart throughout the length of the cables, for the purpose of maintaining the relative positions of the wires with each other and with the sheave wheels *p* and *v*, which are adapted 30 to travel thereon, as will be presently explained. These wheels are mounted for rotation on a frame which may be constructed of ordinary gas pipe and pipe connection, as illustrated, or in any suitable manner; 35 the present construction comprising transverse bars *r* and *t* and longitudinal bars *q* and *s*. To the middle bar *t*, is secured a number of bowed springs *u* having journaled to their respective ends at *w*, the current 40 removing wheels *v*. Of course, the frame must be insulated from the cables *n*, since these cables comprise a track for supporting the truck-like structure, and this insulation may be accomplished by making the hubs 45 *P'* of the wheels *p* of insulating material; such, for example, as shown at *p'*, Fig. 1. The cables *n* are preferably made of steel or iron and the wires or cables *k* are preferably of some good electrical conducting 50 material such as copper.

At *C'* are posts to illustrate suitable means for supporting the ends *n'* of the cables *n*.

The current is conducted through the wheels *v*, the springs *u*, the bar *t* and the 55 down turned end *w* of the bar *t*, and the supporting arms *y*. From these supporting arms, the current is conducted to the motor in any suitable manner, which is not described, as it forms no part of the present 60 invention.

I claim:—

1. In an aerial support for cranes, parallel cables supported at their ends only, cross beams supported by said cables at intervals 65 between the ends of the cables, and electric wires carried only by said beams.

2. In an aerial support for cranes, a single span of parallel cables, cross beams, located at intervals along the span and supported 100 by said cables, electric conductors carried by said cross beams, a truck like structure, wheels therefor resting on said cables, and electric contacts carried by said truck and bearing upon said conductors.

3. In an aerial support for cranes, a num-

ber of supporting cables spaced in parallel relation by spacer beams secured thereto, a number of electric conductors supported and spaced apart by said spacer beams, insulators intervening the conductors and the spacer beams, a frame, wheels connected to the frame adapted to travel on the supporting cables, a bar extending transversely of said frame and having connection with the

frame, curved springs having their middle portion secured to the bar, and sheave wheels on the bar for the purpose specified.

In testimony whereof I have affixed my signature in presence of two witnesses.

BERNHARD CLAUSEN. [L. s.]
